GREASE GUN FILLER

Russell Gunning, Tipton, Ind.

Application March 18, 1937, Serial No. 131,704

2 Claims. (Cl. 221—47.5)

My invention relates to a device for filling grease guns and it consists in the constructions, arrangements and combinations herein described and claimed.

It is an object of the invention to provide a 5 filler means which may be quickly attached to grease containers as shipped from the oil companies, without the need for puncturing or rupturing of the container, and in which the piston of the 10 filler device effectively closes the container against ingress of dirt or foreign matter.

It is also an object of the invention to provide a 15 novel construction of piston, embodying a grease dispensing nozzle through which the grease is dispensed upon downward movement of the piston into the container.

Additional objects, advantages and features of 20 invention will be apparent from the following description and accompanying drawing, wherein

Figure 1 is a side elevation of the filler device, applied to a container, parts being in section, and the piston being shown in raised position.

Figure 2 is a similar view showing the piston in the lower position.

Figure 3 is a top plan view of the device.

Figure 4 is a fragmentary sectional view of an 25 adapter which may be employed with the discharge nozzle.

Figure 5 is a similar view of a further form of 30 adapter.

There is illustrated a container 10, which is packed with grease at the refinery and shipped to the consumer. These containers are closed with a slip-type cover (not shown) which is readily removable to gain access to the grease. With 35 removal of the cover, my filler, generally indicated by the reference character 11, is installed upon the open end of the container.

The filler 11 comprises a mounting ring 12 of 40 a size to fit the circumference of the container 10, the ring being split and the end terminations 13 bent to lie in a plane at right angles to the ring. The terminations are apertured and receive a screw threaded bolt 14 upon which a nut 15 is 45 engaged, the head of the bolt having contacting relation with one termination and the nut bearing upon the other termination. Thus, the ring may be firmly secured to the container.

A yoke 16 is provided, formed from heavy strap 50 metal, bent adjacent its ends to provide downwardly extended legs 17. The legs 17 are spaced so as to embrace the ring 12 to which they are welded. The yoke 16 extends transversely across the ring 12, a suitable distance thereabove and

thus the legs will be disposed upon diametrically opposite sides of the ring.

Upon one end of the yoke 16 there is suitably mounted an upright standard 18 adjacent the upper end of which there is formed an inclined slot 19, receiving the pin 20 of an operating lever 21. The lever 21 is formed from a suitable gauge of sheet metal, bent intermediate its length to provide a pair of spaced parallel levers 22. Between the levers 22 a rack bar 23 is slidably disposed and a pawl 24 is fixed between the levers by means of rivets 25. The pawl 24 is positioned so as to cooperate with the teeth 26 of the rack bar, as will be explained more fully hereinafter. A pin 27 is fixed between the levers 22 extending across the 15 space defined by the levers and serves as a stop means for downward movement of the lever, due to engagement with the adjacent edge of the standard 18.

A piston 28 of a diameter to fit within the 20 container is rigidly connected with the rack 26, the latter passing through a slot formed in the yoke 16. The piston 28 comprises a pair of circular plates 29 and 30, the latter being of slightly less diameter than the former, and between the plates 25 there is a packing ring 31. Due to the lesser diameter of the ring 30 the packing ring may be bent downwardly forming a cup, effecting a seal between the piston and the wall of the container. The plates and the packing ring may be secured 30 together by rivets or otherwise, as desired.

At a suitable point, the plates 29 and 30 have 35 formed therein aligned openings, and within these openings a discharge nozzle 32 is rigidly secured. The nozzle extends upwardly from the piston and is of a length greater than the depth of the container 10, for a purpose presently to be explained. It will be seen that the nozzle is in open communication with the container 10.

The operation

The operation will be readily understood from the following description. With the device installed upon the container, the lever 21 is raised slightly at its pivoted end which is accomplished 45 by reason of the slot 19 which movement also brings the pawl 24 into engagement with a tooth 26 of the rack bar. The lever 21 is now in position to force the piston 28 downwardly for the purpose of discharging grease, and with the 50 grease gun 33 presented over the nozzle 32, such movement is given the lever. The piston 28 moves downwardly compressing the grease and forcing a portion upwardly into the nozzle. Continued downward step-by-step movement of the 55

piston will cause the grease to discharge into the gun 33, and as the gun fills it will move upwardly. This operation is continued until the gun is filled to a desired point or capacity, and is then removed from the nozzle. In order to prevent foreign matter entering the nozzle when not in use, provision is made of a cap 36 which may be inserted over the end of the nozzle.

A hand grip 35 is mounted upon the upper end 10 of the rack bar, for the purpose of returning the piston to its uppermost position. The handle also serves as a means for transporting the container from one place to another.

Inasmuch as grease guns may vary as to the 15 diameter of the barrel portion thereof, in Figures 4 and 5 I have shown modifications of adapters which may be used with the discharge nozzle. In Figure 4, I have shown an adapter 36 which includes a clamp collar 37 and a reduced nipple 38. 20 The adapter 36 may be clamped to the upper end of the discharge nozzle as will be apparent. In Figure 5, the upper end of the nozzle 32 is screw-threaded as at 39, and the interior of the collar 40 of the adapter is similarly threaded, and 25 through these means the adapter may be attached.

It will be obvious that the filler device may be employed in other situations, such as the filling of caulking guns and the like.

30 While I have shown and described a preferred construction, this is by way of illustration only, and I consider as my own all such variations in structure as fairly fall within the scope of the appended claims.

35 I claim:—

1. In combination, a container for grease or the like having an open top, a piston slidably mounted in the container, a yoke detachably

mounted upon the container, said yoke extending above and across the container and having a slot medially thereof, a rack bar on the piston and extended through the slot of the yoke, a standard having an inclined slot, an operating 5 lever including a pin pivotally mounted in the slot of the standard, a pawl on the operating lever cooperable with the teeth of the rack bar to effect downward movement of the piston, means on the lever engageable with the standard 10 to prevent limited downward movement of the lever and a nozzle on the piston in communication with a container, said nozzle extending upwardly above the piston and of a length greater than the depth of the container. 15

2. In combination, a container for grease or the like having an open top, a piston slidably mounted in the container, a yoke member, said yoke comprising a split ring circumscribing the container and having securing means, the yoke 20 having upstanding legs and a transverse member, said transverse member having a slot medially thereof, a rack bar on the piston and extended through the slot of the transverse member, an upright standard on the transverse member, the 25 standard having an inclined slot, an operating lever pivotally mounted in the inclined slot, a pawl on the lever cooperable with the teeth of the rack bar, for effecting downward movement of the piston, hand grip means on the rack bar 30 for returning the piston to raised position, means on the lever engageable with the standard to limit downward movement of the lever, and a nozzle on the upper side of the piston in communication with the container, said nozzle extending upward- 35 ly above the piston and of a length greater than the depth of the container.

RUSSELL GUNNING.
